BOX DISMEMBERING MACHINE

Leon Mann, Mount Vernon, N. Y.

Application July 25, 1934, Serial No. 736,864

13 Claims. (Cl. 254—124)

The improvements relate to means for dismembering or disintegrating boxes, cases and the like so that they may be stored and shipped, knocked down and reassembled for re-use. They may, however, be used for other purposes to which they are adaptable. The primary object and purpose of the improvements is to provide mechanism of efficient and durable construction and certain operation for dismembering egg cases and the like after their tops have been removed and the contents disposed of, so that these cases—many millions of which are used annually in the United States—can be stored and shipped back to distant points where eggs are to be packed, from the localities in which the eggs are sold to the ultimate consumer.

The advantages of the improvements will be recognized by those familiar with the packing and shipment of eggs in cases or crates, the principal item of which is the saving in storage and transportation costs, which are in most cases so great as to render such storage and transportation of the empty cases in their original set up condition prohibitive.

The standard cases of this character are of uniform size, adapted to contain thirty dozen eggs in their packing, and consists of top, bottom, sides, ends and middle partition. The ends and middle partition are made of heavier board than the sides, top and bottom, and the latter are nailed to them but not to one another. The retailer who sells the eggs removes the top of the case and the nails, disposes of the contents of the case, but leaves the remaining parts intact. To dismember or knock down this case by hand is an operation involving considerable labor and damage to the parts of the case, and therefore involves an expense which in many cases renders this operation unprofitable. With the present improvements the case from which the top has been removed can be dismembered or disintegrated and reduced to knock-down condition by a simple and effective machine operation involving a relatively small amount of labor and power—if power be used—so that the cases can be dismembered, stored and shipped to distant points in knocked down condition and sold for re-use at a substantial profit.

The improvements are illustrated in the accompanying drawings, referred to herein, in which—

Fig. 1 is an assembly of a box or a case dismembering mechanism in perspective;

Fig. 2 is a perspective of operating mechanism therefor;

Fig. 3 is a perspective of an egg case such as the mechanism shown is adapted to operate on;

Fig. 4 is a side elevation of the crate of Fig. 3 inverted and of the dismembering mechanism on which it has been placed while in this position;

Fig. 5 is an enlarged detail in perspective of a fragment of one of the toggle operating posts and parts on which it is mounted, the post being shown separated from said parts;

Fig. 6 is an enlarged detail in perspective of one of the box top and nail drawing and spreading claws;

Fig. 7 is a similar view of a similar claw for operating on the sides of the box and their nails;

Fig. 8 is a plan of a box or case partly dismembered, with the dismembering mechanism within the same shown in dotted lines so far as such mechanism is concealed by the said case.

Fig. 9 is an enlarged detail of one of the separating and nail drawing tooth members with fragments of the case showing the teeth entering between the box parts and engaging the nails;

Fig. 10 is an enlarged detail of one of the operating toggles;

Fig. 11 is an enlarged detail showing one of the rod bearings in a cam slot by which the rod is caused to reciprocate.

The details of construction and operation of the illustrated embodiment as herein described will be varied to adapt the improvements to boxes or cases of different sizes and proportions and also to meet conditions arising from differences in the materials and methods employed in manufacturing them, without departing from the scope of the present improvements. Modifications in the details of construction and arrangement may also be made in the illustrated embodiment within the scope of said improvements.

The box dismembering head on which the box or case is to be placed in inverted position comprises essentially pull rods 1, 2, 3, 4, for longitudinal movement of the parts and similar rods 5, 6, 7, 8, for lateral movement. Posts 9, 10, 11, 12, are mounted for both longitudinal and lateral movement and are connected at their tops by cross members 15, 16, 17 and 18, and the said posts and cross members carry projecting double tooth members 19, 20, 21, 22, 23, 24, 25, 26, and toggle bars 27, 28, 29, 30, 31 and 32 are connected with the pull rods and the posts. The pull rods are mounted in sleeves 33, 34, 35, 36, 37 and 38, 33 and 34 being mounted on longitudinal horizontal bottom strips 39 and 40 and sleeves 35 to 38, inclusive, on similar cross strips 41, 42, 43 and 44.

The eight posts 9, 10, 11 and 12 are provided with tongues 13 (see Fig. 5) in their bottoms positioned in slots 39' and 40' in the ends of the longitudinal bottom members, so as to be held 5 against independent lateral movement, and the ends of the bottom cross members 41, 42, 43 and 44 are stepped as shown at 42', 44' so that the ends of the members 39 and 40 resting thereon will be held against inward lateral movement beyond 10 normal position. This arrangement permits the eight corner posts to have longitudinal movement and also lateral movement under the pressure or pull of the toggle bars outwardly and inwardly to a limited extent, and the outward 15 and inward lateral movement carrying with them the members 39 and 40, for the purpose of thrusting the beveled teeth in between the ends and middle partition of the case and the sides and between them and the inverted bottom, in proximity 20 to the nails by which these parts are secured, so that the said parts of the case will be moved apart to a limited extent and the nails partly drawn. To permit the required vertical movement of the toggle bars the sleeves 33 to 38, 25 inclusive are provided with vertical slots 14 through which the said toggle bars pass near their ends which are secured to the pull rods and the posts are also provided with tapering slots 14' into which said bars are inserted, the said bars 30 being connected to the rods by means of a stout pin 27' (see Fig. 4) passing through them and through the rods, and to the posts by other pins 9' passing therethrough.

The egg case to be dismembered by the mechanism 35 shown as an illustrative embodiment of the improvements is a standard case (Fig. 3) slightly in excess of 12 inches in height and width and somewhat more than double that in length, consisting of sides 45, ends 46 and a middle partition 47, a bottom 48 and a top (not shown). It is also usually provided with batten strips 49 at top and bottom of its ends on the outside. These cases are usually made up by nailing sides, top 45 and bottom to the ends and middle partition, the said ends and partition being of about $\frac{1}{16}$ ths inch board and the sides, top and bottom of about $\frac{1}{8}$ ths inch material. Usually there are six horizontal nails driven at equal distances to secure the sides to the edges of the ends and partition and six 50 similar vertical nails driven in like manner to secure the bottom to the said ends and partitions. The tops of the case having been removed before the contents of the case have been disposed of, the case when it is to be dismembered and reduced to knock-down condition is without a top or cover, and such top or cover therefore is not one of the parts to be operated on. The nails employed are usually $\frac{1}{8}$ ths wire nails with approximately a quarter inch of the shank next to the 55 head serrated. The operation of dismembering the case therefore requires movements of slightly less than 10/16ths or $\frac{5}{8}$ ths of an inch. But as the sides and bottom of the box are of light material, and the nails are driven into the ends and partitions more than half an inch it is not feasible to remove the said sides and bottom by pressure against such parts, without first starting and partly drawing the nails. Therefore, it 60 is necessary to employ the beveled teeth to start and partly draw the nails before the said sides and bottom can be removed.

The teeth 19 to 26, inclusive, are of peculiar shape and mounted in a peculiar way to perform 65 their functions. The said tooth members 23 to

26, inclusive are thicker at their inner portion than the similar members 19 to 22, inclusive (see Figs. 6 and 7) and are therefore tapered more steeply toward their points or prongs 26' and 22'. The reason for this provision is that the former group of members are relied upon to draw the nails securing the bottom of the case to the ends and middle partition to a greater extent than the latter, and to such an extent that after the sides have been removed there will be little difficulty 10 in removing the bottom by hand or by means of some convenient hand implement or other device, whereas the sides are removed by the lateral movement of the posts and tooth members in contact therewith, after the teeth have been forced 15 home by the longitudinal movement of the vertical posts and their connecting cross members. The outer sides of the tooth members are plane and the inner sides beveled or tapered outwardly, so that they will act on the principle of the inclined plane in separating the parts between 20 which they are forced and drawing the nails. These members are also provided with crotches 26'' and 22'' so that they have two prongs each and so that each nail will be seated in the bottom 25 of a crotch and its head prevented from slipping past the teeth and pulling through the side or top as it is drawn. If, however, the nails have not been accurately positioned in driving them the oscillating movement of the tooth members will 30 permit them to engage the nails in the manner described. Six tooth members have been provided for each nailed end and middle portion of sides and bottom, one member for each nail, but the number may be increased if a greater number of 35 nails are used or the nails driven irregularly. Those for engaging the nails of the middle partition are alternated, three being mounted on each of the posts 10 and 11 and three on each of the cross members 16 and 17, so that the pressure 40 will be substantially equal on the two sides of the said middle partition.

Lateral oscillatory movement of the tooth members is permitted by a substantially U-shaped spring 50 located in each recess 52 of the posts 45 and top cross members in which the inner ends of the said tooth members are positioned and held by pivot pins 51. The recesses are larger than the inner ends of the tooth members, and the space between them filled by the spring 50, 50 so that if the said members have been rocked or oscillated on their pivots in being forced home they will by the action of the said spring be returned to normal position when withdrawn. The depth of the recesses 52 is such that the flat side 55 of each tooth member is substantially flush with the outer surface of the part in which it is positioned, and so that the said flat surface and the surface of said part will both press against the inner wall of the case. It will be understood 60 that the size and form of the tooth members and adjacent parts and their arrangement may be varied to suit varying conditions in the portions of the box or case upon which they are designed to operate.

In order to facilitate the placing of the case on the dismembering mechanism the upper ends of the posts are beveled, as shown at 12', and a leaf spring 53 is inserted between each top cross member and the tops of the adjacent posts, so 70 that the posts can yield slightly if it is necessary to force a case thereon. The connection between the posts and these top cross members comprises a bead 12'' at the top of the post and a bead 18' on the said cross member aligned therewith, and 75

horizontal U-shaped guides 54 secured to the posts, receiving said beads and holding them in slidable engagement.

In operation the case is inverted and placed over the dismembering mechanism, as shown in Fig. 4, with the middle partition of the case between the posts 10 and 11. To hold the case accurately in position while being operated on, guides 55 are provided for the bottom edges of the partition and 56 for the bottom edges of the ends of the case. The pull rods 1, 2, 3 and 4 are then operated to cause the toggle bars 21, 28, 29 and 30 to move the posts longitudinally toward both ends and the middle partition of the case and force the prongs or teeth carried by the posts to bite in between the sides and bottom of the case and its ends and middle partition, partly drawing the nails and separating the parts secured thereby. The pull rods 5, 6, 7 and 8 are then operated to cause the toggle bars 31 and 32 connected therewith and also with the said posts to force said posts outwardly to remove the sides of the case. The ends, middle partition and bottom of the case are thus left on the machine, with the bottom partly removed from the other parts. The pull rods are then moved upwardly to withdraw the teeth and return the posts to normal position, and the portion of the case remaining on the machine may then be removed and the bottom knocked off. The nails in these operations remain in the sides and bottom of the case when they are removed, but can be easily forced therefrom by pressing the part against a firm flat surface with the points of the nails in contact with such surface, or they may be removed in other suitable manner.

The slots for the pull rods and the toggle bars 31 and 32 should be of sufficient width to allow some lateral movement of these members when the corner posts are moved longitudinally, and should also be of sufficient length to permit the toggle bars to move vertically to a sufficient extent to produce the desired lateral thrust. This movement of the toggle bars in both cases will produce a movement of the parts sufficient for the purpose designed, but it will be understood that they will be of such length and will have such pivotal movement as may be necessary. In the present case, the movements of the posts and teeth are less than one inch, and therefore a toggle bar five inches in length having a downward movement at its power end of less than three inches will produce the desired movement at the work end.

The rods 1 to 8 inclusive, by which the dismembering mechanisms are operated extend through slots 57 and 58 in the base plate 59, on which the said mechanisms are mounted by having the bottom cross members 41, 42, 43 and 44 supported thereon and the other parts supported on said cross members. These rods may be actuated by any suitable source of power and power transmitting means, but as shown are caused to reciprocate by the mechanisms illustrated in Figure 2 in which each rod is connected with a rotary disk having a cam slot therein. The rods 1, 2, 3 and 4, which are first operated to pull their toggle bars and insert the teeth, are connected with disks 61, 62, 63 and 64 and the rods 5, 6, 7 and 8 which are next operated to pull their toggle bars and spread the side members laterally to remove the sides of the case are connected with disks 65, 66, 67 and 68. Each rod has an angular bracket 69 or 70 fixed to it near its lower end and a short shaft 71 mounted in said bracket

and the lower end of the rod in bearings 72, 73, and extends through the cam slot 74 of the disk. Rotation of the disks in counter-clockwise direction pulls down the rods and rotation in the opposite direction raises them again to normal position to retract the teeth and bring the other dismembering parts back to normal position to receive another case or box.

The disks 61 to 64 are keyed on shafts 75 and 76 mounted in any suitable bearing (not shown) and a crank arm 77 keyed on the end of shaft 76 and having a link 78 pivoted at its outer end is provided for rotating the shaft 76 and, through the arms 79 on the shafts and link 80, the shaft 75. Both shafts 75 and 76 are keyed extension shafts normally held in retracted position by tension springs 81 mounted between pins 82 which extend through the slots 83 of the splice member 84 where it dovetails and has sliding relation with the adjacent parts of the shaft, to limit the extension movement of the shaft. This extension movement of the shaft is necessary to permit the cams and their rods 1, 2, 3 and 4 to move laterally when the side members of the dismembering head are spread to remove the sides of the case. A retracting spring 85 is connected with one of the arms 79 at one end and should have its opposite end secured to a fixed part, to rock the shafts 75 and 76 back to normal position or assist therein.

The shaft 86 is adapted to be rocked in a manner similar to the shafts 75, and 76, an arm 87 keyed to one end thereof and having a power imparting link 88 pivotally connected with its outer end being provided for that purpose. This shaft is preferably supported in hangers 89 and 90 which may be pendently supported from the bottom of the base or table 59, and have sleeves 91 and 92 which hold securely the overlapping ends 93 and 94 of the shaft sections, to permit them to slide lengthwise to a sufficient extent to permit the disks keyed thereon and their rods to move longitudinally when the tooth operating toggles expand the corner posts and force the tooth members between the parts of the case to be separated. These parts may be spring or otherwise retracted as may also the parts for operating the teeth.

Any suitable power device may be employed to pull the power links 78 and 88 and the same device may be employed to move them upwardly and restore the mechanisms to their normal or inoperative positions. Thus treadles with sufficient leverage may be employed to move the mechanisms in both directions, or pneumatic, hydraulic or other fluid operated pistons may be used. Such power means are well known and are not shown or described, and are not a part of the present improvements.

The method or process disclosed herein, which may be practiced by other means than those set forth, is a part of the present improvements.

What I claim is:

1. In a box or case dismembering or knocking down machine mechanism adapted to be positioned inside the box comprising expandible members, and means for expanding the same in two directions against and for causing portions of the same to be forced in between vertical and horizontal inner walls thereof at connected portions of said walls to separate said walls from each other.

2. In a box or case dismembering or knocking down machine mechanism adapted to be positioned inside the box comprising expandible

- members, and means for expanding the same in two directions against and for causing portions of the same to be forced in between the inner walls thereof at connected portions of said walls 5 to separate said walls from each other.
3. In a box or case dismembering or knocking down machine, mechanism adapted to be positioned inside the box comprising expandable members, distensible members thereon constructed and arranged to enter between the connected ends of adjacent walls and in proximity to fastening means in said ends and to withdraw such means from one end, and means for expanding the same against the inner walls thereof 10 to separate said walls from each other.
4. In a box or case dismembering or knocking down machine mechanism adapted to be positioned inside the box comprising expandable members, distensible members thereon constructed and arranged to enter between the connected ends of adjacent walls and in proximity to fastening means in said ends and to withdraw such means from one end, and means for expanding the same against the inner walls thereof 15 to separate said walls from each other and means for operating said distensible members and causing them to enter between said connected ends.
5. In a box or case dismembering or knocking down machine mechanism adapted to be positioned inside the box comprising expandable members and laterally distensible members carried therewith, means for operating the said distensible members and causing them to enter 20 between connected ends of the vertical and horizontal inner walls thereof to separate said walls from each other, and means for pressing said expandable members against inner walls to completely disconnect them from other walls.
6. In a box or case dismembering or knocking down machine mechanism adapted to be positioned inside the box comprising expandable members and laterally distensible members carried therewith, means for operating the said distensible members and causing them to enter 25 between connected ends of the vertical and horizontal inner walls thereof to separate said walls from each other, and means for pressing said expandable members against inner walls to completely disconnect them from other walls.
7. In a box or case dismembering or knocking down machine mechanism adapted to be positioned inside the box comprising expandable members and laterally distensible members carried therewith, means for operating the said disten- 30
- sible members and causing them to enter between connected ends of the vertical and horizontal inner walls thereof to separate said walls from each other, and means for pressing said expandable members against inner walls to completely disconnect them from other walls.
8. In a box or case dismembering or knocking down machine mechanism adapted to be positioned inside the box comprising expandable members and laterally distensible members thereon, means for expanding the both classes of members against the inner walls thereof to separate 35 said walls from each other, and other means for distending said distensible members.
9. A mechanism of the kind described comprising operatively connected parts for engaging between and separating members of a box united by fastening means adjacent said fastening means and drawing said fastening means, means for moving such engaging means in different directions to further separate said parts and means for returning them to normal position.
10. In a box or case dismembering or knocking down machine mechanism adapted to be positioned inside the box comprising expandable members, and means for expanding the same in different directions against the inner walls thereof 40 to separate said walls from each other.
11. In a box or case dismembering or knocking down machine mechanism adapted to be positioned inside the box comprising expandable members, and means for expanding the same in different directions against the inner walls thereof to separate said walls from each other, certain of said expandable members having parts constructed and arranged to enter between connected members of the said box or case.
12. In a box or case dismembering or knocking down machine mechanism adapted to be positioned inside the box comprising expandable members, and means for expanding the same in different directions against the inner walls thereof to separate said walls from each other, certain of said expandable members having parts constructed and arranged to enter between connected members of the said box or case in advance of an expanding movement.
13. In a box or case dismembering or knocking down machine, means adapted to be positioned inside the box comprising an expandable device, and means for expanding the same in different directions against the inner walls thereof to separate said walls from each other.

LEON MANN.
